(57) **CLAIM**

The ornamental design for a pet water dispenser, as shown and described.

DESCRIPTION

FIG. 1 is a top, front and left perspective view of a pet water dispenser showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an exploded top, front and left perspective view of the pet water dispenser; and,

FIG. 9 is an exploded bottom, rear and right perspective view of the pet water dispenser.

The dash-dash broken lines in the drawings depict the portions of the pet water dispenser that form no part of the claimed design.

1 Claim, 9 Drawing Sheets
